UNITED STATES PATENT OFFICE.

ADELINE J. CORSCADEN, OF PHILADELPHIA, PENNSYLVANIA, ADMINISTRATRIX OF THOMAS CORSCADEN, DECEASED.

ROLLS FOR CURVING SHEET-METAL PULLEY-RIMS.

SPECIFICATION forming part of Letters Patent No. 694,910, dated March 4, 1902.

Application filed March 28, 1899. Serial No. 710,857. (No model.)

To all whom it may concern:

Be it known that THOMAS CORSCADEN, deceased, formerly of the city and county of Philadelphia, State of Pennsylvania, did invent an Improvement in Rolls for Curving Sheet-Metal Pulley-Rims, of which the following is a specification.

The invention has reference to rolls for curving sheet-metal pulley-rims; and it consists of certain improvements which are fully set forth in the following specification and shown in the accompanying drawings, which form a part thereof.

The object of the invention is to provide suitable rolls for treating sheet-metal blanks to preliminary operations which shall curve and bend the blank both in the direction of its length and also transversely on its lateral edges to such an extent that it may be subsequently treated in suitable dies for the purpose of forming a semicircular rim-blank suitable for the rims of sheet-metal pulleys, such as set out in Letters Patent No. 595,559, December 14, 1897, and No. 575,106, January 12, 1897, to Corsaden. The blanks formed by this improved machine are subsequently treated by dies actuated by hydraulic or other pressure to cause one of the edges of the curved rim to be curled over into a bead and the other edge into a right-angled flange to which the pulley-spokes are secured, the dies and press for such subsequent operation being clearly set out in application Serial No. 689,533, filed August 25, 1898.

In carrying out the present invention a pair of rolls is provided which are adapted to treat a strip of sheet metal in such a manner as to curl over one edge and bend a greater portion of the other edge into an angular rim, the sheet metal being fed between said rolls by suitable means under the control of the operator. The sheet metal so formed passes directly into a second set of rolls, which is designed solely to act upon the said metal in the direction of its length for the purpose of curving the same into a semicircular shape. It will thus be seen that the first set of rolls operate upon the metal transversely to its

length, whereas the second set operate thereon in the direction of its length, the result of the two sets of rolls being the production of a semicircular or approximately semicircular strip having its longitudinal edges respectively curved upward and bent over toward the center of curvature of the blank considered as an entirety. As the widths of the blanks to be treated vary to suit the different width of the faces of the pulleys to be manufactured, it is preferable to provide the first set of rolls, which bend the blank transversely to its length, with a series of removable sections which are preferably so proportioned that by the insertion or removal or transposal of more or less of said sections different widths of rolls may be secured, so as to bring their bending portions nearer or farther apart, as may be required. The second set of rolls is arranged to permit the passage of the lateral bent edges of the blank while curving said blank in the direction of its length. These rolls need not be made adjustable in width.

The invention further comprehends details of construction which will be better understood by reference to the accompanying drawings, in which—

Figure 1 is a side elevation of the improved machine, taken on line xx of Fig. 3. Fig. 2 is an end elevation of the improved machine. Fig. 3 is a plan view of the same. Fig. 4 is a longitudinal section through the rolls on line yy , Fig. 3. Fig. 5 is a transverse section through the blank after being treated by the rolls, and Fig. 6 is a longitudinal section of the same.

E is the main frame of the machine and comprises a base or bed plate and four upward housings of any suitable construction.

A A' comprise one set of rolls—namely, those which operate upon the sheet metal transversely to its length—and K L L constitute the other set of rolls and operate upon the sheet metal in the direction of its length to curve it. Referring to the rolls A A', they are each composed of a series of annular sleeves or sections B, fastened upon the shafts

or mandrels R R' by keys or in any other suitable manner. By examining Fig. 2 it will be observed that the upper roll A has its right-hand end section formed with a beveled surface C and its left-hand end section formed with a curved shoulder portion d, and the lower roll A' has the corresponding end sections formed with an outwardly-beveled flange c and an outwardly-curved flange D, said parts C c coacting together and similarly the parts d D coacting. The plate which is passed between these rolls is rectangular in shape and of considerable length. When passed between the rolls A A', the left-hand edge of said plate T is curved upward, as indicated at t in Fig. 5, while the other or opposite edge is bent upward at an angle, as indicated at t', Fig. 5. Subsequently the curved edge t becomes bent over into a bead, while the angular part T' is bent at right angles to the body part and forms an inwardly-projecting flange. By removing one or more of the intermediate parts of the rolls A A' or by transposing its sections it is evident that the end sections, which perform the bending actions, will be adjusted nearer together to suit narrower-faced blanks. The variation in the width of these sections B enables the proper adjustment for all necessary variations in widths of the faces of the blanks. Ordinarily the wide sections B would never be removed, as they would constitute the sections required to be interposed between the end sections to suit the various widths of blanks to be treated, but it is evident that they may be removable, if so desired. The shaft R' of one of these rolls is provided with the band-wheel f or receives in any other manner the power necessary to drive the machine. The two shafts R R' are geared together by spur-wheels F F, which insure them running at the same surface speeds.

It is essential that the blanks be properly guided between the rolls A A', so as to insure the requisite amount of metal being curved or flanged on the sides of the blank, and to secure this result guides I I' are provided. The guide I may be set at an angle, as indicated in Fig. 1, and is notched to limit the lateral adjustment of the blank. The other guide I' is made L-shaped, and its guiding edge projects toward the rolls, as clearly shown in Fig. 3. This guide is also adjustable to and from the other guide I by means of adjusting devices i to suit different widths of blanks. The blank is placed upon the guide I, which is of considerable length, and then pushed toward the rolls and between the gripping-jaws H H of the hand-lever G. The lower of these jaws is held in an upright position by a spring h, and the upper jaw is free. The gripping-surfaces of these jaws are arranged eccentric to their pivots. It will now be observed that when the plate is shoved into position till it about reaches the rolls A A' the lever G is

thrust forward, which action causes the plate to be gripped and forcibly pushed between the rolls A A'. As soon as the plate is gripped by the rolls it is driven forward and the jaws H H automatically release their action upon it, and the plate continues to pass forward. It is evident that any other suitable feeding mechanism may be employed, if so desired, though the above-described apparatus has been found excellent in practice. It is also to be understood that the blanks to be treated by the rolls A A' may be ordinary flat blanks, or, if desired, the lateral edges may be slightly bent upward by a previous operation.

After the blank has been treated in the rolls A A' it moves forward and is received between the rolls K L L. The rolls A A' are geared to the rolls K L L by connecting-gears J J' J², so as to insure the speeds of the two sets of rolls being commensurate relatively one to the other. These rolls comprise a large upper roller K and two small rolls L L. The upper roller K is positively driven; but it is not necessary that the lower rolls L L should be positively driven; but they may be so, if desired. The blank in passing between the rolls K and L is curved upward, the said curvature being proportional to the amount of depression of the lower part of the operating-surface of the roller K below the upper edges of the lower rolls L L, and this may be adjusted by the screw M and suitable spacing-strips, as is well known. After the blank passes between the rolls K and L it will be curved to the shape shown in Fig. 6. The roller K, being on the side of the greatest curvature, must be so formed as to permit the passage of the flanged edges t t'. The edge t' is permitted to freely pass by simply making the roller K short, as indicated in Fig. 3; but the surface of the roller at the other end is grooved, as at K', so that for different widths of blank the curved edge t will be permitted to pass forward through one of said grooves, and thereby not injured. It is evident that, if desired, different widths of rollers K might be employed; but this is not essential, as the grooved roller obviates the necessity of loss of time in dismantling and rearranging the roller K, and, furthermore, the portions of the roller between the grooves are amply sufficient for holding the plate down to the rollers L L, insuring the curvature of said plate.

By the employment of rolls of the character herein described the plates may be rapidly and accurately flanged and curved to suit the requirements of subsequent operations in the press and the single machine herein disclosed is suitable for flanging rims for a large variety of pulleys of different diameters and widths of faces.

While the construction herein illustrated is preferred, it is evident that the minor details may be modified without departing from the principles of the invention.

Having now described the invention, what is claimed as new, and desired to be secured by Letters Patent, is—

1. In a machine for shaping blanks for pulley-rims, the combination of two independent sets of positively-driven rolls arranged in alinement, one set being of itself adapted to bend the lateral edges of the plate by acting upon the metal transversely to its length, and the other of which is wholly of itself adapted to act independently on the metal sheet and bend it in the direction of its length to curve it the construction being such that the bending action of each set of rolls is independent of the other set and the main roll of the set of curving-rolls being formed with annular reduced portions for receiving the flanges of the sheet and preventing flattening them out, and gearing to positively drive each set of rolls to enable them to operate at relatively definite speeds.

2. In a machine for shaping blanks for pulley-rims, the combination of two independent set of rolls arranged in alinement but at a considerable distance apart one set being adapted to bend the lateral edges of the plate by acting upon the metal transversely to its length, and the other of which is adapted to bend the sheet in the direction of its length to curve it independently of any action of the first-mentioned set of rolls and the main roll of the set of curving-rolls being formed with annular reduced portions for receiving the flanges of the sheet and preventing flattening them out, and connecting-gearing between the first and second sets of rolls whereby the second set of rolls is positively driven and its speed is commensurate with that of the first set of rolls.

3. In a machine for shaping sheet metal to form pulley-rims, the combination of a pair of rolls adapted to act upon the sheet transversely to its length for the purpose of flanging the lateral edges thereof, two fixed guides I I' for guiding the metal into said rolls one of said guides I having an oblique face, and feeding devices located near the other guide for forcing the metal into said rolls comprising a movable lever portion having gripping-jaws provided with flat gripping-surfaces to grip the sheet on the side farthest from the oblique guide-face when moved toward the rolls and release it upon being moved away from the rolls or when the sheet is pulled between the jaws in the direction of the rolls.

4. In a machine for shaping sheet metal to form pulley-rims, the combination of a pair of rolls adapted to act upon the sheet transversely to its length for the purpose of flanging the lateral edges thereof, guides for guiding the metal into said rolls comprising guide I' presenting a vertical guide-face and oblique guide I presenting an oblique face and longitudinal guide-shoulder, and feeding mechanism consisting of a pivoted lever G, two gripping-jaws H, H, pivoted to the lever and hav-

ing eccentric gripping-surfaces opposed to each other, and a suitable spring h to hold the lower gripping-jaw upward in a normal position.

5. In a machine for shaping blanks for pulley-rims, the combination of a set of rolls adapted to bend the lateral edges of the plate by acting upon the metal transversely to its length for flanging the lateral edges thereof, an independent set of rolls arranged in line with the first-mentioned pair of rolls and operating solely of themselves for curving the sheet blank in the direction of its length and consisting of a large bending-roll and two smaller rollers arranged close to the face of the larger roller and between which and the larger roller the sheet-metal blank is caused to pass, the large bending-roll having reduced portions in diameter for receiving the flanges of the sheet and preventing flattening them out and gearing between the first and second sets of rolls whereby the speed of the second set of rolls is commensurate with that of the first set of rolls and each set of rolls positively operate upon the sheet to perform its function independently of that being performed by the other.

6. In a machine for shaping blanks for pulley-rims, the combination of two flanging-rollers adapted to work together having adjustable sections whereby said sections may be transposed so as to adjust the flanging portions as to their working length to correspond to different widths of blanks between the lateral flanged portions thereof without changing the length of the body of the rolls, and means for feeding a sheet of metal between the said flanging-rollers.

7. In a machine for shaping blanks for pulley-rims, the combination of two flanging-rollers adapted to work together having adjustable sections whereby they may be adjusted as to their working length to correspond to different widths of blanks between the lateral flanged portions thereof, means for feeding a sheet of metal between the said flange-rollers, and a set of curving-rollers arranged to the rear of the flanging-rollers and comprising a curving-roller at one level formed with grooves about its periphery to receive the flanges at one edge and the sheet treated in the flanging-rollers, and two rollers at a different level working in conjunction with the curving-roller whereby the flanged sheet is then curved in the direction of its length.

8. In a machine for shaping blanks for pulley-rims, the combination of flanging-rollers adapted to work together having shafts fitted with adjustable sections abutting against each other and clamped together whereby they may be adjusted as to their working length to correspond to different widths of blanks between the lateral flanged portions thereof, and a set of curving-rollers arranged to the rear of the flanging-rollers.

9. In a machine for shaping blanks for pul-

ley-rims, the combination with a pair of flanging-rollers with curving devices arranged to the rear of the flanging-rollers and comprising a curving-roller formed with grooves about its periphery to receive the flanges of the sheet treated in the flanging-rollers, and guiding devices for holding the flanged sheet against the curving-roller while passing in contact therewith.

In testimony of which invention I have here-^{to} unto set my hand.
